CLAIM

The ornamental design for a pad for a urinal or toilet mat, as shown and described.

DESCRIPTION

FIG. 1 is a front perspective view of a pad for a urinal or toilet mat showing my new design;

FIG. 2 is a front view thereof, the back view is a mirror image of the front view;

FIG. 3 is a right side view thereof, the left side view is a mirror image of the right side view;

FIG. 4 is a top view thereof; and,

FIG. 5 is a bottom view thereof.
